LEE F. BERTHOLD AND WILLIAM LOUDEN, OF FAIRFIELD, IOWA, ASSIGNEES TO THE LOUDEN MACHINERY COMPANY, OF FAIRFIELD, IOWA, A CORPORATION OF IOWA

ELEVATED TRACKWAY

Application filed February 25, 1928. Serial No. 256,976.

Our invention relates to trackways for overhead carriers, made suitable for different constructions of buildings in which the trackways are used, and it consists in making the trackway of different sizes of track-rails and joining them together to suit the conditions encountered, as hereafter shown and described. Also, of improvements in the details of construction which will be hereafter shown and described, and more definitely set forth in the claims.

In the accompanying drawings, forming a part of this specification, Fig. 1 is a side elevation of a trackway embodying our invention, some parts of the connections being in section and the ends and central portions being broken away to economize space in the drawing, and to keep it within required limits. Figs. 2, 3, 4 and 5 are vertically disposed transverse sections on lines 2—2, 3—3, 4—4, and 5—5 respectively of Fig. 1, looking horizontally in the direction of the arrows pointing to said lines in Fig. 1, the lateral dimensions of Fig. 4 being somewhat reduced. Fig. 6 is substantially a horizontally disposed transverse section on line 6—6 of Fig. 1, looking upward in the direction of the arrow. Fig. 7 is a side elevation of a supported trackway which will be hereafter explained. Fig. 8 is a vertically disposed transverse section on line 8—8 of Fig. 7.

Fig. 9 is a side elevation of a section of a still larger and stronger trackway with a trolley thereon. Fig. 10 is a vertically disposed transverse section on the line 10—10 of Fig. 9, looking in the direction of the arrow, and its lateral dimensions being somewhat reduced. Fig. 11 is an enlarged vertical transverse section on line 11—11 of Fig. 9, which may represent either a transverse section of the track-rail shown in that figure, or a still larger track-rail. The proportions of these figures are intended to represent only the general preferred forms of the parts, and not

the proportions required in actual use, as will be hereafter explained.

Referring to the drawings, A represents a section of one of the larger track-rails, broken away near its center, and B and C are sections of different forms of smaller track-rails which are joined by splicing means to opposite ends of the larger track-rail A, said sections of the smaller rails being broken away at their outer ends, and also near their centers. The sections of the rail represented by B is known to the art as the double headed track-rail, because it has beads D and E on the upper and lower edges of vertically disposed central webs thereon, as shown most clearly in Fig. 2. The rail represented by C is known as the single beaded track-rail, because it has only one bead F on the upper edge of its vertically extended central web, as shown most plainly by Fig. 5.

Both of these track-rails B and C, as well as the larger track-rail A, are provided with horizontally disposed wheel supporting flanges G, extended outwardly from the vertically disposed webs on the rails. These wheel supporting flanges G must be of substantially the same dimensions, and when the ends of the different track-rails are joined together they must all be in substantially the same alignment, as shown in Fig. 1. When thus dimensioned and aligned, and a trolley, such as that represented by H is placed on the flanges G of any of the track-rails, its wheels I will be free to run on said flanges G from one end to the other of the trackway.

The trackway is supported in elevated position by track hangers secured thereto at certain points, and then connected to overhead supports, but before going into the details of construction, it will be well to make known the special advantages, and consequent improvements in using different sizes of track-rails in the same trackway. So far as the track-rails B and C are concerned, it is not necessary that both should be used in the same

trackway, and generally both are not so used, unless there should be an insufficient supply of either to complete the trackway. Both styles are shown in the drawings to make it clear that different styles of the smaller track-rails may be used if desired, the only essential being that the wheel supporting flanges *G* must always be of substantially the same dimensions and have the same alignment.

In regard to the larger track-rail *A*, its use in connection with either one or both, of the smaller track-rails *B* or *C*, or any equivalent of them, is to supply a want that is frequently felt in the use of overhead trackways and to make the same, in a number of cases, more practical and less expensive. As already stated, overhead trackways are generally held in elevated position by track hangers secured to the track-rail every few feet apart, and then connected to adjacent overhead supports, but it is well known that these necessary overhead supports are not always available in such a way that any practical form of track hangers can be easily connected to them. Sometimes the trackway has to be run through an open space in a building having no available overhead supporting means, or between buildings where there is no overhead supporting means of any kind.

In such cases this deficiency has to be made good by building up or furnishing a superstructure of some kind, which superstructure is generally expensive, and sometimes objectionable in other respects. In ordinary cases of this kind, where the span is not too long, one of the most practical and least objectionable forms of an improvised overhead supporting means is shown by Figs. 7 and 8. It consists of a large I-beam *J* supported in position at each end by suitable means, not shown which will be strong enough to carry the load without central supports. From this I-beam a track-rail *K* is held in position by a series of track hangers *L* properly secured to the trackway *K* and connected to the I-beam *J*. A large wooden beam might be used instead of the I-beam but usually the I-beam is preferable. While this arrangement may in a number of cases fairly take the place of normal overhead supporting means, and be less objectionable than a regular built up superstructure, it is nevertheless somewhat expensive and also somewhat complicated and objectionable.

With the I-beam *J* there will have to be the track-rail *K* below it, and also the track hangers *L* to connect the track-rail to the I-beam. Our invention eliminates these last items, thus saving their expense and also making the structure more simple and really more practical. The main essential is to make the lower flanges *G* of a large specially constructed track-rail *A*, substantially the same dimensions as the wheel supporting flanges of the smaller track-rail or rails, and then connect-

ing the ends of these smaller track-rails to the large special track-rail *A*, so that their wheel supporting flanges will all be in substantially the same alignment, whereby the wheels of the trolley *H* will run freely on said lower flanges *G* of said larger track rail as well as on the wheel supporting flanges *G* of the smaller track-rails, thus eliminating the track-rail *K* below the I-beam and also the hangers necessary to connect it to the I-beam.

This arrangement enables the user to have a light and inexpensive track-rail where it can be normally supported to carry the load required, and at the same time, to use a heavier and stronger track-rail where it cannot be normally supported, instead of having to use the heavier and more expensive track-rail throughout the entire length of the trackway, or to have to build up an expensive and complicated superstructure to properly support the lighter track-rail where it cannot be otherwise properly supported. This may also be readily done with all sizes of overhead trackways, whereby they may be adapted to carry all kinds of loads from the lightest to the heaviest.

To fully carry out this advantage, all that is necessary is to procure a still larger track rail *M* of the pattern of the rail *A*, being substantially a specially constructed I-beam with wider flanges on one edge of the web than on the other, the narrower flanges of the larger rail being substantially the same dimensions as the wider flanges *N* on the rail *A*. We now turn over the rail *A* and as shown in Fig. 9 join it to the larger rail *M* in the same way as the rails *B* and *C* were joined to the rail *A*. The flanges on which the trolley wheel run are always on the lower edge of the track-rails and must always be of substantially the same dimensions and in substantially the same alignment.

When arranged in this way the wheel *O* of a larger trolley *P* will run on the larger flanges *N* of the rail *A* and the smaller flanges *Q* of the rail *M*, as shown in Fig. 9, the same as the wheels *I* of the trolley *H* will run on the flanges *G* of the track-rails *A*, *B* and *C*, shown in Fig. 1. If necessary, the trackway can be again enlarged by getting another and still larger track-rail of the type similar to *A* and *M* and having its smaller flanges correspond with the larger flanges *R* of the rail *M*. Then turn over the rail *M* so its larger flanges *R* will be below and also join it to the smaller flanges of this larger track rail in the manner described.

In Fig. 1 the track rails *B* and *C* are shown supported by hangers *S* and *T* of usual type connected to overhead supports, such as the beams *U*. It is necessary that the ends of the track-rails *A* and *B* or *C*, as well as the larger track rail *M*, or any still larger track-rail which takes its place, should be securely connected together. This may be done in any

suitable manner, but as an improvement in the details of our invention, we have devised a combined track hanger and connecting splice V which, besides connecting the adjoining ends of the larger and smaller track-rails together, can also be used to connect the trackway to overhead supports, such as the beams U, or to any other available overhead support.

- 10 This combined track hanger and splice connection V is preferably composed of two parts which are connected to the web of the track-rail A and also C, by rivets W, as most plainly shown in Figs. 3, 5 and 6, and to the track-rail B by being clamped on the upper bead D or by any other suitable means to hold the rails securely in place. As shown, these plates are provided with large upstanding links X which may be connected to the overhead beams U, or to any other available overhead supporting means. Instead of the links X any other suitable connecting means may be used to connect the combined hanger and splice plate V to available overhead supports.
- 25 In the hanger part X¹ of the splice plates V which connect the rails A, B and C together a bolt W' may be used instead of a rivet, as shown most plainly in Fig. 2.

As will be seen by the drawings, it is necessary that the upper and lower flanges on the track-rails A and M, or on any additional larger track-rails that may be used, shall be of different widths, and that the narrower flanges thereon shall correspond with the wheel supporting flanges of the smaller track-rails used therewith. Also, that the wider flanges on said rails, such as N on track-rail A and R on rail M, shall correspond with the narrower flanges of the next larger track-rails, which may be used therewith.

It will also be seen that smaller and larger trolleys can be used with the track-rail A, or with any larger rails which are constructed in the same way—that is, having narrower flanges on one side and wider flanges on the other. When the narrower flanges of the rail A are below, the flanges Y of the wheels I must be limited in their diameters so they will not come in contact with the wider upper flanges N of the rail A, as shown in Fig. 4, but when turned over, as shown in Figs. 9 and 10, the wheels O of the larger trolley P may have flanges Z which will extend up beyond the narrow flanges G. The same will also be the case when the track rail M is turned over to become the smaller rail in combination with a still larger track-rail.

While it is preferable to use track-rails having flanges on opposite sides of a vertically disposed central web or webs, as shown in Figs. 2, 3, 4, 5, 10 and 11, other forms of track-rails may be used, if desired, provided means be used to properly balance them. Also that the larger wheel supporting means of the smaller rail will properly align with the

smaller wheel supporting means of the next larger rail, so that larger and smaller trolleys may be used on the rails by simply turning the rails upside down, as shown in Figs. 4 and 10.

One object of our invention is to have the track-rails A and M and also any larger similar track-rails which may be used, to reach when possible, across any span where there may be practically no available overhead supporting means. In order to accomplish this result as far as possible, the central webs of the rails should be made wider, or in other words, higher in proportion to the widths of the horizontal flanges than is shown in the drawings, in order to give the rails the greatest strength. These webs were narrowed in the drawings to economize space, and to keep within the limits of the sheets containing the drawings.

There may be instances where the span will be too great and one or more central supports of some kind—an arch or otherwise—may be required. Our invention does not require impossibilities, but only, as far as possible, to do away with central supports where overhead supporting means is not readily available. In all such cases there will be a material saving in the use of our invention, which is simple in construction and practical in operation, being adapted to accommodate itself to the different conditions encountered in the use of overhead trackways.

Our invention is also intended to permit the use of different sizes of trolleys with each of the different sizes of track-rails by having a larger size of a wheel supporting flange or flanges, on one edge of the rail web, and a smaller wheel supporting flange or flanges on the other edge of the web, whereby by turning the track-rail upside down, larger or smaller trolleys may be used on the larger or smaller wheel supporting flanges.

What we claim is—

1. In elevated trackways, the combination of different sizes of track-rails having their adjoining ends connected together to form a continuous trackway, the smaller track-rails being adapted to be placed where a series of overhead supports are available, and the larger and stronger track-rails being adapted to be placed where said overhead supports are not available.

2. In elevated trackways, the combination of different sizes of track-rails having their adjoining ends connected together to form a continuous trackway, the smaller track-rails being adapted to be placed where a series of overhead supports are available, and the larger and stronger track-rails being adapted to be placed where said overhead supports are not available, said track-rails having wheel supporting means in alignment with each other, whereby a trolley may pass over

said wheel supporting means from one end of the trackway to the other.

3. In elevated trackways, the combination of different sizes of track-rails having their adjoining ends connected together to form a continuous trackway, said track-rails each having a central vertically disposed web with horizontally disposed wheel supporting flanges on opposite edges thereof, the flanges on the opposite edges of the web being of different widths, whereby trolleys of different sizes will be adapted to run on the different widths of wheel supporting flanges.

4. In elevated trackways, the combination of different sizes of track-rails having their adjoining ends connected together to form a continuous trackway, said track-rails each having a central vertically disposed web with horizontally disposed wheel supporting flanges on opposite edges thereof, the flanges on the opposite edges of the web being of different widths, whereby trolleys of different sizes will be adapted to run on the different widths of wheel supporting flanges, the wider flanges on the smaller track-rails being of substantially the same size as the smaller flanges on the next larger track-rail, whereby when said flanges are in alignment a trolley may run thereon from one end of the track-way to the other.

5. In elevated trackways, the combination of different sizes of track-rails having different sizes of wheel supporting flanges on opposite edges of each track-rail, the smaller wheel supporting flange of one rail corresponding in size with the larger flange on the next smaller rail, whereby either of the rails by turning their flanges up or down may be connected with the next larger or the next smaller rail, to form a continuous trackway.

6. In elevated trackways, the combination of different sizes of track-rails having adjoining ends connected together to form a continuous trackway, the smaller track-rails being adapted to be placed where a series of overhead supports are available, and the larger and stronger track-rails being adapted to be placed where said overhead supports are not available, and splicing means connecting adjacent ends of said track-rails together and being provided with means to connect said rails to overhead supports and to thereby hold the trackway in elevated position.

7. In elevated trackways, the combination of different sizes of track-rails having their adjoining ends connected together to form a continuous trackway, the smaller track-rails being adapted to be placed where a series of overhead supports are available, and the larger and stronger track-rails being adapted to be placed where said overhead supports are not available, and splicing parts applied to the meeting ends of said track-rails and secured thereto, and means to connect said splicing parts to overhead supports, whereby

the trackway will be held in elevated position.

8. In elevated trackways, a track-rail section having on its upper and lower edges trolley supporting flanges of different widths, said rail section being adapted to be turned upside down, whereby it may be connected with rail sections having trolley supporting flanges of similar widths, so that trolleys of suitable sizes may run thereon.

Fairfield, Iowa, February 23, 1928.
